US00D421263S

United States Patent [19]

Phillips

[11] Patent Number: Des. 421,263

[45] Date of Patent: ** Feb. 29, 2000

[54] PLANAR MAGNETIC TRANSDUCER

[75] Inventor: Scott Phillips, Victoria, Canada

[73] Assignee: Sonigistix Corporation, Richmond, Canada

[**] Term: 14 Years

[21] Appl. No.: 29/093,070

[22] Filed: Sep. 2, 1998

[51] LOC (6) Cl. 14-01

[52] U.S. Cl. D14/222

[58] Field of Search D13/101; D14/222; 381/398, 399, 408, 431

CLAIM

The ornamental design for a planar magnetic transducer, as shown and described.

DESCRIPTION

FIG. 1 is a front perspective view of a planar magnetic transducer showing our new design;

FIG. 2 is a front elevational view thereof, a rear elevational view being a mirror image;

FIG. 3 is a left side view thereof, a view from the right side being a mirror image;

FIG. 4 is a top plan view; and,

FIG. 5 is a bottom plan view.
